UNITED STATES PATENT OFFICE.

JOSEPH JOULE AND CHARLES ALBERT COUPS, OF BELLEVILLE, NEW JERSEY,
ASSIGNORS TO EASTWOOD WIRE MANUFACTURING COMPANY, OF BELLE-
VILLE, NEW JERSEY, A CORPORATION OF NEW JERSEY.

LOOM.

1,353,963.

Specification of Letters Patent. Patented Sept. 28, 1920.

Application filed March 4, 1916, Serial No. 82,028. Renewed April 30, 1920. Serial No. 378,011.

To all whom it may concern:

Be it known that we, JOSEPH JOULE, a citizen of the United States, and a resident of Belleville, in the county of Essex and State of New Jersey, and CHARLES ALBERT COUPS, a subject of the King of Great Britain, and a resident of Belleville, in the county of Essex and State of New Jersey, have jointly invented certain new and useful Improvements in Looms, of which the following is a specification.

The invention pertains more particularly to improvements in let-off and take-up mechanisms for looms, and more especially to the take-up mechanism, and we illustrate the invention as embodied in a loom for weaving wire cloth of the character required for use in paper making machines, this wire cloth being of very fine mesh and requiring the utmost uniformity throughout its entire extent.

The loom illustrated in the drawings presents some well known features, these being the warp beam, breast beam, cloth beam and lay beam frame, these features being illustrated for the purpose of disclosing the nature of our present invention, which has to do with the mechanism whereby the warp wires are fed and kept under tension and the cloth as formed is wound upon the cloth beam.

The invention will be fully understood from the detailed description hereinafter presented, reference being had to the accompanying drawings, in which:

Figure 1 is a side elevation of a sufficient portion of a loom to illustrate our invention;

Fig. 2 is a horizontal section, on a larger scale and partly broken away, through a portion of the loom, taken on the dotted line 2-2 of Fig. 1;

Fig. 3 is a vertical section, partly broken away and looking at the inner face of the left hand side frame, and

Fig. 4 is a view partly in section and partly broken away of a detail looking at the inner face of the right hand side frame of the loom.

In the drawings, 10 designates suitable side supporting frames for the loom parts, 11 the customary warp beam, 12 the breast beam, 13 the cloth beam, 14 the lay beam, 15 a transverse beam upon which a shuttle

carriage may be mounted in a well known manner, and 16 the warp wires, all of the features just mentioned being well known in this art.

17 designates the driving shaft upon one end of which is mounted a belt wheel 18 to be driven by a belt 19, as usual. Upon the driven shaft 9 is mounted a cam wheel 20 having two angularly projecting cam portions 21 to engage the point of a pivotally mounted lever arm 22 whose shank end has 65 pivotally connected with it a pawl 23 which cooperates with a ratchet wheel 24 for driving the shaft 25 by intermittent motions. The shaft 25 has secured upon its outer end a bevel gear wheel 26 which is in mesh with 70 a bevel gear wheel 27 mounted on a longitudinal shaft 28 upon whose rear end is secured a bevel gear wheel 29 which is in mesh with a bevel gear wheel 30 secured on the lower end of a vertical shaft 31 whose upper 75 end carries a worm 32 in mesh with a gear wheel 33 secured on the shaft of the warp beam 11. During the rotation of the driven shaft 9, the cam projections 21 are, one after another, carried under the free end of the 80 lever arm 22 with the result of tilting said arm on its pivotal support and causing it through the pawl 23 to impart intermittent rotary motion to the ratchet wheel 24 and shaft 25. The motion of the shaft 25 is 85 communicated through the gear wheels 26, 27, shaft 28, gear wheels 29, 30, worm 32 and gear wheel 33 to the warp beam 11, with the result that said warp beam will be rotated intermittently to release therefrom 90 slight portions of the warp wires 16 with each motion of the beam.

The mechanism just hereinbefore described has to do with the unwinding of the warp wires from the warp beam, and it will 95 be observed that this unwinding of the warp wires is accomplished by brief accurate intermittent motions of the warp beam.

The means for placing a tension on the warp wires and winding the cloth upon the 100 cloth beam 13 will now be described. The cloth as woven is drawn over the breast beam 12 and wound upon the cloth beam 13.

The cloth beam 13 has upon the end of its shaft a sprocket wheel 34 upon which is 105 mounted the lower loop of an upwardly and rearwardly extending endless sprocket chain 35, the upper loop of said chain being upon

a small sprocket wheel 36. The sprocket wheel 36 is secured upon a transverse shaft 37 mounted in the side frames 10 of the loom, and upon said shaft 37, adjacent to the sprocket wheel 36, is secured a sprocket wheel 38 upon which is placed the upper loop of a sprocket chain 39. The sprocket chain 39 extends downwardly and then upwardly and over a small sprocket wheel 40 which is secured on a transverse shaft 41 carrying a ratchet wheel 42. One side or reach of the sprocket chain 35 is slack and one side or reach of the sprocket chain 39 is slack and extends over an idler 43 and thence upwardly and upon the sprocket wheel 40, while the other side or reach of the sprocket chain 35 is taut and likewise the other side or reach of the sprocket chain 39 is taut and extends around under a pulley wheel 44 from which is suspended by a rod 45 a series of weights 46, there being a series of the weights so that one or more may be made use of as occasion may require. The weights 46 through their rod 45 and pulley wheel 44 exert a strong tension on the loop 47 of the sprocket chain 39. Upon the right hand side-frame 10 we mount a series of pawls or dogs 48 which engage the toothed wheel 42 and resist the tendency of the weights 46 to, through the chain 39 and sprocket wheel 40, turn the shaft 41 in a reverse direction, said weights by means of said pawls 48 and wheel 42 being prevented from drawing the chain 39 forwardly over the wheel 40 and descending to the extent that might otherwise be permitted thereby. One purpose of the weights 46 acting on the chain 39 is to rotate in a proper manner and whenever permitted so to do, the sprocket wheel 38 and sprocket wheel 36 in a direction to cause the travel of the taut or upper side of the chain 35 over said sprocket wheel 36 and effect through the rotation of the sprocket wheel 34 that movement of the cloth beam 13 which will wind the cloth thereon. While the weights 46 act against the sprocket wheel 40, shaft 41 and toothed wheel 42 they are prevented by the pawls or dogs 48 from drawing the sprocket chain 39 toward the front over said sprocket wheel 40 and their action places a tension on the chain 39 whereby the wheel 38 is caused through the sprocket chain 35 and sprocket wheel 34 to place a tension on the warp wires 16 and also rotate the cloth beam 13 in a direction to wind up the cloth as made. The warp beam intermittently releases the warp wires and the weights 46 prevent slackness in said wires by placing the wires under tension and also effecting the winding of the cloth on the beam 13.

The rotary motion imparted to the cloth beam 13 by the weights 46 and the chains and connections just hereinbefore described 65 is intermittent and timed with the move-

ment of the lay and the rotation of the warp beam. With each partial rotation of the sprocket wheel 38, sprocket wheel 34 and cloth beam 13, a portion of the chain 39 at the rear side of the sprocket wheel 38 will travel downwardly toward the weights 46 and the weights 46 will elongate the loop 47 at such times accordingly. It is desired however that the weights 46 shall not travel all the way down to the floor or other support, and hence we provide means for restoring said weights to their elevated position with each movement of the lay toward the rear. The descent of the weights 46 takes place while the lay is making its beat, 80 and thereafter when the lay is returned toward the rear, the weights 46 are elevated by the mechanism shown more particularly in Fig. 3, in which 49 designates a lever arm swiveled on the shaft 41, 50 a pawl carried by said lever arm, 51 a ratchet wheel rigidly secured on said shaft and engaged by said pawl and 53 a crank arm rigidly secured at its front end to the lay and at its rear end connected by means of a flexible chain or the like 52 to said lever arm 49. With each operation of the lay to beat the weft, the crank arm 53 will turn downwardly and due to the flexibility of the chain 52 will have no effect on the lever arm 49, but with each backward movement of the lay, the crank arm 53 will be swung upwardly and, drawing on the chain 52, pull the lever arm 49 upwardly and cause the pawl 50 to rotate the ratchet wheel 51, shaft 41 and sprocket wheel 40 toward the rear, with the result that while the forward portion of the chain 39 is acting against the warp beam and warp, said pawl 50 by its co-operation with the sprocket wheel 40 will cause the rear portion of the sprocket chain 39 to travel upwardly and rearwardly over said sprocket wheel 40, thus raising the weights 46. With each backward movement of the lay, after its beat, the crank arm 53 and lever arm 49, through the pawl 50 and ratchet wheel 51, effect a limited rotation of the sprocket wheel 40 sufficient to elevate the weights 46 to the extent that said weights descend while the lay is making its beat. 115

We provide a cord or other flexible connection 54 on the lay 14 (Fig. 3) and connect the same with the lever arm 49 for the purpose of rendering the connection between said lever arm and crank arm 53 inoperative during such time as it may be necessary to repair the cloth on the machine and move the lay in doing so. At such times it is desired that when the lay 14 is moved, the lever arm 49 may not operate to 125 elevate the weights 46. The cord 54 extends from a winding knob 55 upwardly over a pulley-wheel 56 and thence rearwardly over a pulley-wheel 57 suspended from the crank arm 53 and thence down- 130

wardly to the lever arm 49, a spring 58 being interposed in said cord to relieve the cord of slackness during such time as the loom is in regular operation. When it is 5 desired to repair the cloth on the loom and at the same time be able to move the lay without actuating the lever arm 49, the attendant will, by turning the knob 55, wind the cord 54 thereon to such extent as to 10 elevate the forward end of the lever arm 49 sufficiently to place such slackness in the chain 52 that said chain will be incapable of affecting the lever arm 49 during such periods as the lay may be moved while the repair 15 of the cloth is taking place. The cord 54 performs no duty while the loom is in regular operation and is present merely as a convenient means for rendering the lever arm 49 inoperative preparatory to the repairing 20 of the cloth.

We shall preferably provide at each side of the loom the chains and their sprocket wheels and weights, shown in Fig. 1, or in other words duplicate said chains, sprocket 25 wheels and weights at each side of the loom, but ordinarily the one gear wheel and worm for the warp beam will be sufficient.

The operation of the loom will be understood without further detailed explanation. 30 The warp beam rotates intermittently to feed off warp wires and the weight 46 is suspended and acts against the warp beam to wind the cloth thereon as woven and tension the warp strands, and means are provided operable by the lay for maintaining 35 the weight substantially in a given position. The movement of the weight both downwardly and upwardly is very slight, and hence the weight is automatically maintained in substantially the initial position 40 given to it.

What we claim as our invention and desire to secure by Letters-Patent, is:

1. In a loom, in combination, a warp-beam, a cloth-beam, a lay, means for rotating the warp-beam to feed the warp-wires, a suspended weight acting against the cloth-beam to wind the cloth thereon as woven and tension the warp-strands, and means comprising pawl and ratchet mechanism after each beat of the lay for automatically elevating the said weight and thereby maintaining the same substantially in a given position.
2. In a loom, in combination, a warp-beam, a cloth-beam, a lay, means for intermittently rotating the warp-beam to intermittently feed the warp-wires, a suspended weight acting against the cloth-beam to 50 wind the cloth thereon as woven and tension the warp-strands, and means comprising pawl and ratchet mechanism after each beat of the lay for automatically elevating the said weight and thereby maintaining the same substantially in a given position.

3. In a loom, in combination, a warp-beam, a cloth-beam, a lay, means for rotating the warp-beam to feed the warp wires, a weight, means suspending said weight and connected with the cloth beam to wind the 70 cloth thereon and tension the warp strands, and means operable by the lay for maintaining the weight substantially in a given position, the means suspending the weight comprising a sprocket chain and sprocket wheels 75 upon which the chain is mounted and in a loop of which chain the weight is held suspended.

4. In a loom, in combination, a warp-beam, a cloth-beam, a lay, means for rotating the warp-beam to feed the warp wires, a weight, means suspending said weight and connected with the cloth beam to wind the 80 cloth thereon and tension the warp strands, and means operable by the lay for maintaining the weight substantially in a given position, the means suspending the weight comprising a sprocket chain and sprocket wheels 85 upon which the chain is mounted and in a loop of which chain the weight is held suspended, and said chain being adapted to travel in one end portion in a direction to permit the weight to descend slightly on the rotary motion of the cloth beam, and the means for maintaining the weight substantially in a given position being a pawl 90 arm engaging the shaft of the sprocket wheel at the other end portion of the said chain and a crank arm connected with the lay and having a flexible connection with 95 said pawl arm, whereby on the movement of the lay in one direction, said crank arm may actuate said pawl arm to effect the upward travel of a portion of said chain and thereby elevate the weight to the extent that it 100 had previously descended.

5. In a loom, a warp-beam, a cloth-beam, a lay, means for rotating the warp-beam to feed the warp wires, and means for rotating the cloth-beam to wind the cloth thereon 110 as woven and tension the warp strands comprising a sprocket wheel on the end of the cloth beam shaft, a sprocket wheel on an auxiliary shaft, a sprocket chain connecting said sprocket wheels, a second sprocket 115 wheel on said auxiliary shaft, a sprocket wheel on a second auxiliary shaft, a chain connecting said last mentioned sprocket wheel and said second sprocket wheel and downwardly looped between said wheels and 120 a weight suspended in said loop of said chain and acting against one portion of the chain to effect the winding of the cloth beam, combined with means for preventing said second auxiliary shaft from rotating 125 under the force of said weight, and means for, at predetermined intervals, rotating said second auxiliary shaft to effect the upward travel of a portion of the chain-loop suspending said weight, whereby said weight 130

while descending on the winding of the cloth beam is elevated on the rotation of said second auxiliary shaft.

6. In a loom, a warp-beam, a cloth-beam, 5 a lay, means for rotating the warp-beam to feed the warp-wires, and means for rotating the cloth-beam to wind the cloth thereon as woven and tension the warp strands comprising a sprocket wheel on the end of 10 the cloth beam shaft, a sprocket wheel on an auxiliary shaft, a sprocket chain connecting said sprocket wheels, a second sprocket wheel on said auxiliary shaft, a sprocket wheel on a second auxiliary shaft, 15 a chain connecting said last mentioned sprocket wheel and said second sprocket wheel and downwardly looped between said wheels and a weight suspended in said loop of said chain and acting against one portion 20 of the chain to effect the winding of the cloth beam, combined with means for preventing said second auxiliary shaft from rotating under the force of said weight, and means for, at predetermined intervals, rotating said second auxiliary shaft on the 25 back stroke of the lay to effect the upward travel of a portion of the chain-loop suspending said weight, whereby said weight while descending on the winding of the 30 cloth-beam is elevated on the rotation of said second auxiliary shaft.

7. In a loom, in combination, a warp-beam, a cloth-beam, a lay, means for rotating the warp-beam to feed the warp wires,

a weight, means suspending said weight and 35 connected with the cloth beam to wind the cloth thereon and tension the warp strands and means after each beat of the lay for automatically elevating the said weight and thereby maintaining the same substantially 40 in a given position, the means suspending the weight comprising a sprocket chain and sprocket wheels upon which the chain is mounted and in a loop of which chain the weight is held suspended. 45

8. In a loom, in combination, a warp-beam, a cloth-beam, a lay, means for intermittently rotating the warp-beam to intermittently feed the warp-wires, a weight, 50 means suspending said weight and connected with the cloth beam to wind the cloth thereon and tension the warp strands and means after each beat of the lay for automatically elevating said weight and thereby maintaining the same substantially in a 55 given position, the means suspending the weight comprising a sprocket chain and sprocket wheels upon which the chain is mounted and in a loop of which chain the weight is held suspended. 60

Signed at Belleville, in the county of Essex and State of New Jersey, this 24 day of February, 1916.

JOSEPH JOULE.

CHARLES ALBERT COUPS.
